FIG. 9

FIG. 4

FIG. 5

FIG. 6

FIG. 7

FIG. 8

FIG. 10

FIGURE 1 is a side elevational view of a bottle showing my new design wherein the grip portion of the bottle is provided with a plurality of alternating narrow concave bands and wide convex bands.

FIGURE 2 is an end elevational view thereof.

FIGURE 3 is a cross-sectional view taken along the plane of line 3—3 of FIGURE 1.

FIGURE 4 is a perspective view of a bottle thereof.

FIGURE 5 is a side elevational view of a bottle showing an alternative design wherein the grip portion of the bottle is provided with a plurality of alternating narrow convex bands and wide concave bands.

FIGURE 6 is an end elevational view thereof.

FIGURE 7 is a cross-sectional view taken along the plane of line 7—7 of FIGURE 5.

FIGURE 8 is a perspective view thereof.

FIGURE 9 is a partial cross-sectional view taken along the plane of line 9—9 of FIGURE 1.

FIGURE 10 is a partial cross-sectional view taken along the plane of line 10—10 of FIGURE 5.

The characteristic features of this design reside in the configuration shown in the full lines on the drawings which design is a bottle having a substantially rectangular cross-section, the corners of which are rounded. The shoulders of the bottle slopes outwardly and downwardly from the neck and opposite sides of the bottle are provided with an indented grip portion. This application is a continuation of my applications, Ser. Nos. 70,645 and 70,482, filed June 21, 1962, and June 8, 1962, respectively and now abandoned.

I claim:

The ornamental design for a bottle, substantially as shown and described.
